UNITED STATES PATENT OFFICE.

KARL G. DIETERICH, OF NEW YORK, N. Y.

LOCKING SAFETY-PIN.

No. 873,927.

Specification of Letters Patent.

Patented Dec. 17, 1907.

Application filed December 27, 1906. Serial No. 349,619.

To all whom it may concern:

Be it known that I, KARL G. DIETERICH, a subject of the German Emperor, residing at the city of New York, borough of Brooklyn, 5 Kings county, in the State of New York, have invented certain new and useful Improvements in Locking Safety-Pins, of which the following is a full, clear, and exact specification.

10 My invention relates generally to fastening devices and the same has for its object more particularly to provide a simple, efficient and reliable safety pin which is so constructed that it will be stronger and capable 15 of withstanding greater strain than such pins are commonly able to withstand.

Further said invention has for its object to provide a safety pin wherein its pointed end may be securely locked within the cap or 20 guard.

Further said invention has for its object to provide a safety pin wherein the pin member proper when locked with its cap or guard will serve to strengthen the entire structure, 25 and prevent the pin member becoming bent under strain and its end withdrawn from its cap or guard.

To the attainment of the aforesaid objects and ends my invention consists in the novel 30 details of construction, and in the combination, connection and arrangement of parts hereinafter more fully described, and then pointed out in the claims.

In the accompanying drawings forming 35 part of this specification wherein like numerals of reference indicate like parts. Figure 1 is a side view of a safety pin constructed according to and embodying my said invention, the same being shown open in full lines, 40 and closed in dotted lines; Fig. 2 is a section taken on the line 2—2 of Fig. 1, looking downward; Fig. 3 is a section taken on the line 3—3 of Fig. 1; Fig. 4 is a detail section taken on the line 4—4 of Fig. 3; Fig. 5 is a 45 detail perspective view of the cap or guard, detached from the pin; Fig. 6 is a detail view illustrating a modified form of pin, and Fig. 7 is a similar view illustrating a further modified form of pin, designed to be used in safety 50 pins of small size made of wire of small gage.

In said drawings 10 designates the pin as a whole formed essentially of a single piece of wire, and comprising a substantially straight body-portion 11, a pin 12, and a spring 13 55 provided at the junction of said body-portion 11 and pin 12. The body-portion 11 near its

inclosed end is bent inward and outward again to form a guide 14 which is tapered towards its end and serves to guide the point end of the pin 12 into the cap or guard. The 60 end 15 of the body-portion 11 is bent at right angles to the longitudinal axis of the pin, and its extreme end 16 is again bent inward and parallel with said axis.

17 denotes the cap or guard which is 65 formed of a single piece of sheet metal and comprises a tubular portion 18 which is clamped to the end of the body-portion 11 and surrounds the portions 15 and 16 thereof. The inner end of said cap terminates in two upwardly extending separated parallel side plates or members 19, 19 adapted to receive intermediate the same the point end of the pin 12. The extreme rear ends of plates or members 19, 19, are bent 70 toward each other to form lugs 20, 20. The upper edges of said lugs 20, 20 are rounded at 21, 21, and the vertical opposing edges thereof are slightly tapered and meet at the 75 lower edge of the cap or guard where the 80 same form a substantially semi-circular recess 22 adapted to receive the point end of the pin 12. The lugs 20, 20 of the side plates or members are bent forward as best shown at Figs. 2 and 4.

85 The pin 12 is provided upon its opposite sides adjacent to its point end with parallel vertical recesses or notches 23, 23 which are so positioned that the same will be engaged by the inwardly projecting lugs 20, 20 of the 90 cap or guard 17 when the end of the pin is in position therein, and serve to hold the point end of said pin 12 securely attached thereto.

In the modification illustrated at Fig. 6, 95 the engaging recesses of the pin 25 are annular. With either form of recess as shown in this figure, and also in Figs. 1, 2 and 3, there may be a plurality of recesses arranged side by side in order to insure the end of the pin being securely engaged by the ends of the 100 lugs where the pin itself becomes bowed under a strain, and consequently so shortened that it could not be properly engaged were it only provided with a single notch or recess.

At Fig. 7 I have illustrated a further form 105 of pin, and in this construction the pin 28 is provided adjacent to its point end with an enlarged portion 29 which tapers in both directions, and provided at its thickest part with an annular recess 30. It will of course 110 be obvious that any number of such recesses whether vertical or annular may be provided.

The construction here illustrated is more particularly designed for small pins which are usually made of small stock and for that reason could not be recessed without weakening 5 the same.

The uses and operations of the devices are obvious. It is to be noted, however, that in my improved form of safety pin the point end is not only secured against lateral movement, but also against longitudinal movement, due usually to the bending or bowing of the pin 12 under strain or tension, and that in my said constructions this strain or tension is taken advantage of, for the greater 10 15 20 25

the strain or tension on the pin 12 becomes, the tighter will the lugs 20, 20 of the cap due to their toggle-like action engage the recesses or groove in the pin, and in this way the resiliency of the body-portion 11 is utilized to maintain the locking engagement with the pin 12; while the strain or tension is resisted not only by the pin proper, 12, but by the entire structure.

Having thus described my invention, what 25 I claim and desire to secure by Letters Patent is:

1. A safety pin comprising a body portion, a pin extending therefrom, a cap secured to said body portion provided with inwardly 30 and forwardly projecting lugs adapted to engage said pin and wedge the end thereof intermediate said lugs under tension of said pin, substantially as specified.
2. A safety pin comprising a body portion, a cap secured thereto provided with inwardly and forwardly projecting lugs, and a pin extending from said body portion adapted to be engaged by the lugs on said cap, substantially as specified.
3. A safety pin comprising a body portion, a cap secured thereto provided with inwardly and forwardly projecting lugs having their inner edges arranged substantially parallel to

each other, and a pin projecting from said body portion adapted to be engaged by the lugs on said cap, substantially as specified.

4. A safety pin comprising a body portion, a cap secured thereto provided at its rear end with inwardly and forwardly projecting lugs and a pin projecting from said body portion provided with recesses adapted to engage the lugs on said cap, substantially as specified.

5. A safety pin comprising a body portion, a cap secured thereto comprising a plurality of parallel side plates, inwardly and forwardly projecting lugs on said side plates, and a pin projecting from said body portion provided with recesses adapted to be engaged by the ends of the lugs on said side plates, substantially as specified.

6. A safety pin comprising a body portion, a cap secured thereto at one end provided at its rear end with inwardly and forwardly projecting lugs having their vertical edges free and arranged substantially parallel to each other, and a pin projecting from said body portion provided with recesses adapted to be engaged by the vertical edges of the lugs on said cap, substantially as specified.

7. A safety pin comprising a body-portion, a cap secured thereto provided at its rear end with inwardly and forwardly projecting lugs, a pin at the other end of said body-portion, and a plurality of annular recesses arranged side by side in said pin adjacent to its free end adapted to be engaged by the lugs on said cap, substantially as specified.

Signed at the city of New York, in the county and State of New York, this twenty-fourth day of December, nineteen hundred and six.

KARL G. DIETERICH.
